UNITED STATES PATENT OFFICE.

HUGH WILSON GILCHRIST AND JOHN JAMES REID, OF ANACONDA, MONTANA.

CORNER CONSTRUCTION FOR FLUMES, TROUGHES, LAUNDERS, AND THE LIKE.

Application filed September 12, 1924. Serial No. 737,434.

To all whom it may concern:

Be it known that we, (1) HUGH WILSON GILCHRIST and (2) JOHN JAMES REID, citizens of the United States, residing at 5 Anaconda, in the county of Deerlodge and State of Montana, have invented certain new and useful Improvements in Corner Constructions for Flumes, Troughs, Launders, and the like, of which the following is a 10 specification.

The invention relates to corners for wooden flumes, troughs, launders and the like for the conveyance of water, solutions or other liquids. The principal uses of such devices 15 are in metallurgical, irrigation and analogous operations; the liquid often carrying solids in suspension. It will be understood however that the present improvements are not limited in use to the particular industries 20 mentioned, but are useful in any liquid carrying device of the trough type which is constructed wholly or partly of wood and in which it is necessary or desirable to have the corners in contact with the liquid substantially 25 liquid-tight.

In the ordinary type of wooden flume, the corners at the juncture of the sides and bottom are formed by spiking the lower side planks to the respective outer bottom 30 planks, the butt joints between the planks being made tight by calking with oakum or the like. Under this practise the spikes must be closely spaced to prevent leakage through the corner joints, and since the 35 spikes must be driven into the edges of the bottom planks they line up in a nearly straight line. As a consequence the side planks invariably split along this line. Besides, such a construction requires close 40 spacing of the yokes or spaced frames which hold the flume together. In addition, the seams require attention and renewal of the calking from time to time.

The corner construction which is the subject 45 of the present invention is entirely free from the difficulties referred to and has besides certain additional advantages, referred to hereinafter.

The novel construction contemplates the 50 use of relatively heavy timbers as the chief corner elements, these timbers being aligned end to end throughout the length of the flume or trough, and special means being provided at the abutting ends to insure 55 liquid-tight joints.

The invention will better be understood by

reference to the accompanying drawing, wherein one embodiment of the invention is illustrated and wherein:

Fig. 1 is a cross-section of a flume in 60 which our corner construction is employed;

Fig. 2 is a side view of a portion of the flume where two corner timbers meet; and

Fig. 3 is a detail, perspective, inside view 65 of a joint.

The flume or trough illustrated comprises side walls 10, bottom 11 and corner members 12. The walls and bottom may be formed by edge on edge alinement of two or more planks splined together as at 13 70 along the meeting edges. Each corner member is prepared from a timber 14, which is relatively heavy as compared with the thickness of the planks 10, 11, and the adjacent planks are joined along their edges to the 75 timber by suitable splines or the like 15. The timber 14 is beveled along one corner as at 16 to afford a smooth surface within the flume; otherwise it may be rectangular, preferably square, in cross-section. 80

Depending upon the length of the flume, two or more of the timbers 14 are arranged in alinement end to end, the joint as thus formed being indicated at 17 in Figs. 2 and 3. The section shown in Fig. 1 is taken 85 centrally through such joint. It is a particular object of this invention to make joints 17 liquid-tight. For this purpose two holes, preferably at right angles to each other, are provided at each of the joints, these holes 90 intersecting within the timber 14. The holes may conveniently be bored from the top and inner side of the timber along the center lines of the surfaces, in which case the holes will intersect of course at the center of the 95 timber when the latter is square in cross-section. Part of each of the holes, conveniently one-half as shown in the drawing, is formed in the end of one timber, while the complementary portions of the holes are 100 formed in the abutting end of the adjacent timber. In each of the holes thus provided there is driven a soft pine dowel 18, or its equivalent, which will swell when in contact with the liquid carried by the flume and thereby make the butt joint tight against 105 leakage therethrough of liquid from the flume. While we have mentioned soft pine dowels, these being especially suitable for the purpose, it will be understood that other 110 woods or materials which will swell under the particular conditions of use may be em-

ployed. The dowels 18 when in place as shown in the drawing lie flush at their outer ends with the surfaces of the timber and the adjacent side and bottom planks 10, 11 cover the openings and dowel ends 19 wholly or partially to prevent the dowels from coming out. This is the chief consideration in locating the dowel holes with respect to the width of the timbers and the thickness of the planks.

The flume is strengthened by the usual yokes comprising the side members 20 and the top and bottom members 21.

It will be seen that by the construction described we have provided a flume corner which is not only liquid-tight but which also adds materially to the stiffness and strength of the flume, and therefore reduces the number of frames or yokes required to hold the flume together and keep it tight. Also, the improved construction obviates the necessity for any nailing whatever at the corners; and the dowel arrangement provides a joint which will remain tight for the life of the flume. Furthermore, alternate freezing and thawing will not open the joint.

Certain variations are of course possible and, as will be obvious, any construction in which there is employed between such abutting ends an insert element capable of swelling under the conditions of use to close the joint but over a section less in area than the full cross-section of the ends, regardless of the number of component parts of said insert elements, is the full equivalent in its broader scope of that part of the invention which relates to the liquid-tight joint between the abutting ends of the timbers.

We claim:—

1. A corner construction for polygonal section flumes or the like comprising relatively heavy timbers held end to end and constituting angle-pieces, and liquid-tight joints between the adjacent ends of the timbers.

2. A corner construction for polygonal section flumes or the like comprising relatively heavy timbers held end to end and constituting angle-pieces, and joints between the adjacent ends of the timbers capable of becoming liquid-tight in the use of the flume.

3. A corner construction for polygonal section flumes or the like comprising relatively heavy timbers held end to end and constituting angle-pieces, and means providing a liquid-tight joint between adjacent ends of the timbers comprising an insert element capable of swelling upon contact with the liquid to be confined in the flume.

4. A flume or the like of polygonal cross-section comprising relatively heavy timbers held end to end and constituting angle-pieces, bottom and side-wall members secured to faces of said timbers edge-on, liquid-tight joints between the adjacent ends of the tim-

bers, and liquid-tight joints between the timbers and said bottom and side-wall members.

5. A flume or the like of polygonal cross-section comprising spaced, relatively heavy timbers constituting angle-pieces, side-wall members secured to upper faces of said timbers edge-on, a bottom member secured to the inside faces of said timbers edge-on, liquid-tight joints between the timbers and said side-wall members and liquid-tight joints between the timbers and said bottom member.

6. A corner construction for polygonal section flumes or the like comprising relatively heavy timbers held end to end and constituting angle-pieces, and means providing a liquid-tight joint between adjacent ends of the timbers comprising a pair of plugs capable of swelling upon contact with the liquid to be confined in the flume, said plugs being arranged within the timbers at the joint at an angle to each other and contacting at their inner ends.

7. A corner construction for flumes or the like of polygonal cross-section comprising relatively heavy timbers held end to end and constituting angle-pieces, bottom and side-wall members secured to faces of said timbers edge-on, and means between the adjacent ends of the timbers capable of swelling upon contact with the liquid to be confined in the flume to provide a liquid-tight joint and extending from the adjacent edge of the side-wall member to the adjacent edge of the bottom member.

8. A corner construction for flumes or the like of polygonal cross-section comprising relatively heavy timbers held end to end and constituting angle-pieces, bottom and side-wall members secured to faces of said timbers edge-on, and means providing a liquid-tight joint between the adjacent ends of the timbers, said means comprising a pair of swellable plugs arranged within the joint at an angle to each other and contacting at their inner ends, the outer ends of the plugs being confined respectively beneath the adjacent edge of the side wall member and the adjacent edge of said bottom member.

9. A corner construction for flumes or the like of polygonal cross-section comprising relatively heavy timbers held end to end and constituting angle-pieces, bottom and side-wall members secured to said timbers edge-on and at a right angle to each other, and means providing a liquid-tight joint between the adjacent ends of the timbers, said means comprising a pair of swellable plugs arranged within the joint at a right angle to each other and contacting at their inner ends, the outer ends of said plugs being confined respectively beneath the adjacent edge of the side-wall member and the adjacent edge of said bottom member.

10. A corner construction for flumes or the like of polygonal cross-section comprising relatively heavy timbers held end to end and constituting angle-pieces, bottom and 5 side-wall members secured to said timbers edge-on, said timbers being beveled substantially along a plane joining the inner edges of the bottom and side-wall members adjacent the timbers, and means providing a 10 liquid-tight joint between the adjacent ends of the timbers, said means comprising an insert element capable of swelling upon contact with the liquid to be confined in the flume and extending across the joint beneath the 15 bevel from the adjacent edge of the side-wall member to the adjacent edge of the bottom member.

11. A corner construction for flumes or the like of polygonal cross-section comprising 20 relatively heavy timbers held end to end and constituting angle-pieces, and means providing a liquid-tight joint between the adjacent ends of the timbers, said means comprising a pair of plugs capable of swelling 25 upon contact with the liquid to be confined in the flume and arranged at an angle to each other and contacting within the joint at their inner ends; one half of each of said plugs being seated within the end of one of 30 the timbers and the other half of each of the plugs being seated within the end of the other of the timbers.

12. A corner construction for flumes or the like of polygonal cross-section comprising 35 relatively heavy timbers held end to end and constituting angle-pieces, bottom and side- wall members secured to said timbers edge-on and at a right angle to each other, said timbers being beveled substantially along a plane joining the inner edges of the bottom 40 and side-wall members adjacent the timbers, and means providing a liquid-tight joint between the adjacent ends of the timbers, said means comprising a pair of plugs capable of swelling upon contact with the liquid to be 45 confined in the flume and arranged within the joint at a right angle to each other and contacting at their inner ends and together extending across the joint beneath the bevel from the adjacent edge of the side-wall 50 members to the adjacent edge of the bottom member, the outer ends of the plugs being confined respectively beneath the adjacent edge of the side-wall member and the adjacent edge of the bottom member; one half 55 of each of said plugs being seated within the end of one of the timbers and the other half of each of the plugs being seated within the end of the other of the timbers.

13. In combination, a pair of timbers of 60 substantial cross-section held end to end and forming part of a liquid-confining structure, and a liquid-tight joint between the adjacent ends of the timbers comprising a pair of 65 swellable plugs arranged within the timbers at the joint, contacting at their inner ends and extending at their outer ends substantially to the sides of the timbers.

In testimony whereof, we affix our signatures.

HUGH WILSON GILCHRIST.
JOHN JAMES REID.
